CLAIM

The ornamental design for a hair straightening apparatus, as shown and described.

DESCRIPTION

Figure 1.1 is a perspective view of a hair straightening apparatus from above and the right side showing my new design;

Figure 1.2 is another perspective view thereof;

Figure 1.3 is top view thereof;

Figure 1.4 is a bottom view thereof;

Figure 1.5 is a front view thereof;

Figure 1.6 is a rear view;

Figure 1.7 is a left side view thereof;

Figure 1.8 is a right side view thereof;

Figure 1.9 is a right side perspective view thereof; and

Figure 1.10 is a right side view thereof with the hair straightening apparatus being in an open position.
